METHOD OF DRYING AND IMPREGNATING FELT

Filed Nov. 5, 1934

UNITED STATES PATENT OFFICE

2,050,483

METHOD OF DRYING AND IMPREGNATING
FELT

Harold D. Brown, Los Angeles, Calif.

Application November 5, 1934, Serial No. 751,539

2 Claims. (Cl. 91—70)

My invention relates to a new and improved method of impregnating or saturating an absorbent material with a saturant. This application is a continuation in part of my application entitled "Method of drying and saturating felt", Serial No. 682,105, filed July 25, 1933.

Although my invention is useful in many of the arts wherein felt, paper or similar material is impregnated with asphalt or other saturant, my 10 invention has a particular utility in the roof-producing industry, and therefore in the ensuing description I will describe my invention as particularly applied to that industry. It should be understood that I do not wish thereby to limit 15 my invention to the particular illustration of this application.

It is an object of my invention to provide a method of saturating an absorbent with a saturant to obtain a superior product at less cost.

20 A further object of my invention is to provide a method in which the absorbent, such as a sheet of felt or the equivalent, is submerged in a body of saturant, such as hot asphalt or the equivalent, for a sufficient length of time to coat the surfaces 25 of the absorbent, and then to immediately remove the absorbent in order that the vapors formed within the absorbent may escape on the outside of the body of saturant.

By actual use of my invention I have found 30 that it is superior to the prior art methods of drying and saturating a sheet of absorbent such as felt (a) because the apparatus employed for performing the process may be operated at a high rate of speed, (b) because more saturated felt 35 may be produced in a given time, (c) because there is a saving in labor, and (d) because there is a saving in fuel or power required to operate the apparatus and to maintain the saturant at the desired temperature. In actual practice I 40 have found that the saving which is perfected in connection with items (a) to (d) just recited is approximately 20% in each instance. This value, however, may vary depending upon actual operating conditions.

45 A further object of my invention is to provide a process which will simultaneously remove the moisture from the absorbent and saturate the absorbent.

It is an object of my present invention to provide 50 a method in which asphalt is applied to the surfaces of the strip of absorbent material by submerging same in a body of hot asphalt, and removing the strip of felt with such rapidity that the moisture will not materially form into vapors 55 while the strip of felt is still submerged. In this

manner the vapors are formed on the outside of the body of asphalt, where they will be liberated without forming foam in the asphalt. This has the decided advantage of enabling better penetration of the asphalt by preventing formation of foam on the surface of the body of asphalt as well as on the surfaces of the strip of felt. 5

It is a further object of my invention to provide a method of this character in which any foam which may be formed on the surface of the asphalt will be quickly and automatically removed.

It is another object of my invention to provide a method in which a strip of absorbent material may be impregnated in a shorter period of time than is possible by any of the common methods. 15

By the utilization of my invention it is possible to operate apparatus for impregnating the felt at such speeds that with given materials and with a given degree of saturation, larger quantities may be produced in a given length of time than is 20 possible by common methods.

It is an object of my present invention to provide a method of producing asphalt impregnated felt in which the strip of felt or other absorbent material is coated with asphalt or other saturant 25 and in which shortly thereafter the saturant by a suitable pressural operation is forced into the absorbent material.

In the preferred form of my invention I use a pressure means which operates against the surfaces of the strip of felt and which forces the saturant into the strip of felt. In the continuous process of my invention I find that this step in my process may be satisfactorily performed by the use of a pair of rollers, one of which rests on 30 the upper surface of the strip of felt and produces a squeezing action which squeezes or forces the asphalt into the felt strip. 35

The important steps of my invention may be used in the various combinations of other steps 40 which are ordinarily performed in the saturating of an absorbent material. I will describe and illustrate one form of my invention, and it should be understood that various alterations and modifications may be made without departing from 45 the spirit and scope of my invention, and various steps which do not constitute the essence of my invention may be eliminated without departing from the spirit and scope of my invention.

I will now refer to the accompanying drawing 50 and describe the preferred form of my invention.

In the drawing:

Fig. 1 is a somewhat diagrammatic view illustrating the apparatus of my invention. 55

Fig. 2 is a vertical section through the pressure rollers of the invention adapted to impart a surface pressure to the strip of roofing material in the process of treating the same, this section being taken as indicated by line 2—2 of Fig. 1.

Referring particularly to the drawing, I provide a relatively long and shallow tank construction 11 which is inclined downwardly to the left. In the embodiment shown this tank construction 11 is provided with a partition 12, which divides the tank construction into tanks or receptacles 13 and 14. To the left of this pair of tanks 13 and 14 I provide a large saturating tank 15.

The numeral 16 indicates a hot saturant supply pipe which, in the form of my invention disclosed, is adapted to supply hot asphalt to the apparatus. This pipe 16 has a downwardly extending branch 17 which extends into the tank 15 on the left of a partition 18 and has a branch pipe 19 which extends into the tank 15 on the right of the partition 18. This partition 18, it will be noted, divides the tank into two compartments 20 and 22. The hot asphalt is continuously supplied to these two compartments 20 and 22 by means of the branch pipes 19 and 17 and is continuously removed therefrom by suitable return pipes 25.

The main supply pipe 16 is provided with a pair of branch pipes 30 and 31, each of which has a valve 32 and which is adapted to supply hot asphalt to the tanks 13 and 14. By means of the branch pipes 30 and 31, a body of hot asphalt may be maintained in each of the tanks 13 and 14, these bodies of hot asphalt being indicated by numerals 33 and 34. By continuously supplying hot asphalt to each of these tanks 13 and 14, the hot asphalt in one tank is caused to overflow the dividing wall or partition 12, which defines the leftward boundary of the compartment 13 and will spill into the body of hot asphalt in the compartment 14. It will be noted that the upper end of the partition 12 is lower than the rightward wall of the tank 11, and that the leftward wall 35 of the tank 11 is lower than the upper end of the partition 12 in order that a continuous flow will occur over the upper edges of the partition 12 and the wall 35 in a leftward direction, as indicated at A and B in Fig. 1, the overflow indicated at B spilling into the compartment 20 of the tank 15. The partition 18 of the tank 15 also provides a spillway between the compartments 20 and 22, the asphalt overflowing continuously from the compartment 20 into the compartment 22 as indicated at C in Fig. 1.

From the description thus far, the manner and method of supplying hot asphalt to the various tanks and compartments will be understood. The bodies of hot asphalt in the tanks 13, 14 and 20 are continuously replenished and continuously overflow the walls or partitions 12, 35 and 18 which define the left margin of these tanks.

It should be understood, however, that I do not wish to be limited to the specific construction shown in the drawing which is illustrative only, the number and arrangement of the compartments in the tanks 11 and 15 being, of course, dependent upon the desired number of submerging steps in the practice of my novel method, and coming well within the scope of my basic idea.

In each of the tanks 13 and 14 is a guide means in the form of an adjustable roll, these adjust-

able rolls being identified by the numerals 40 and 41. It will be noted that each roll is located below the surface of the body of hot asphalt contained in each of the tanks 13 and 14. The strip of felt or other absorbent material 45 which is to be treated first passes over initial rolls 46 and then passes to the roll 40. In passing around the roll 40, the sheet of felt is submerged in the body 33 of hot asphalt. The strip of felt then passes upwardly and between a pair of pressure rollers 10 P, the purpose of which will be described later. The strip of felt then passes around the roll 41 and then passes around an elevated roll 48.

From the roll 48 I show the strip of felt 45 passing around a guide roll 50 which is adjustably supported in the compartment 20 of the tank 15 by a supporting mechanism 51, including a vertically movable carriage 52 to which is connected suitable cables 53 passing over pulleys 54 which in turn are connected to a suitable operating mechanism which includes a hand wheel 55 adapted when turned to raise or lower the guide roll 50 relative to the tank 15 for the purpose of submerging the strip 45 to a greater or lesser depth in the body of hot asphalt 56 in the compartment 20.

From the adjustable guide roll 50 the felt strip is passed upwardly between a pair of pressure rollers P' which are similar to the rollers P and which are suitably supported on the top of the tank 15. From the pressure rollers P' the felt strip is again passed downwardly around a guide roll 57, adjustably supported by mechanism 58, similar to the supporting mechanism 51.

The felt strip 45 is then carried upwardly and passed between a pair of steam heated gauging rollers H, which are provided with suitable mechanism for varying the distance between the rollers for the purpose of gauging the thickness of the felt strip and of removing the excess asphalt from the surface thereof, in a manner well known in the art.

From the gauging mechanism H the strip 45 is passed upwardly around an elevated roll 59. This roll 59 and the elevated roll 48 are preferably steam heated by suitable well known means to prevent asphalt from collecting and hardening on the surfaces thereof.

In the preferred form of my invention I provide adjustable guide rolls 60 and 61 in the compartment 22 which are comparable to the guide rolls 50 and 57 in the compartment 20.

The guide rolls 60 and 61 are respectively supported by adjustable mechanisms 62 and 63 comparable to the mechanisms 51 and 58.

Mounted on the top of the tank 15 between the mechanisms supporting the guide rolls 60 and 61 is a pair of pressure rollers P'', identical with the pressure rolls P and P'. The strip 45 is carried from the roll 60 between the pressure rollers P'' and is then passed around the guide rolls 61 and is then passed out of the tank 15 and between a pair of suitable steam heated gauge rollers G, similar to the gauge rollers H. The strip 45 is then passed to a suitable cooling loop or over any suitable guides, such as a series of rollers similar to the roller 65 provided for guiding the strip out of the apparatus.

Referring first to the pressure mechanisms P, P', and P'', for accomplishing the step in the process of applying surface compression to the felt strip 45, it should be understood that these mechanisms may be used at various places on the apparatus. I have found it sufficient to utilize only one of such pressure mechanisms, such

as the mechanism P' at a point between the guide rollers 50 and 57 of the compartment 20, so as to provide the surface compression step of the process directly after the strip 45 has passed around the roller 50. It may be found to be desirable, however, to associate one or more of these pressure mechanisms with the tank 11 so as to accomplish a surface compression to the felt strip 45 between the successive steps of submerging the strip in the tanks 13 and 14. For the purpose of illustration I have shown the pressure mechanism P positioned above the tank 11 so that the initial surface compression step in the process is accomplished directly after the initial submerging step in the tank 13.

It may also be found desirable to associate one or more of the pressure mechanisms with the compartment 22 of the tank 15. If such a use is desired, one of the pressure mechanisms such as the mechanism P'' may be positioned between the guide rolls 68 and 61 of the compartment 22, as shown.

The details of construction and the mode of operation of the pressure mechanisms P, P', and P'' will be understood more easily with reference to Fig. 2 of the drawing. In this figure I show a pair of brackets 75 and 76, suitably mounted, such as in the manner shown, on opposite sides of the tank 15, or on a framework above the tank 11, as the case may be. Each of the brackets 75 and 76 provides a bearing 77 adapted to journal a shaft 78 carrying a bed roller 79, which in the preferred form of apparatus is provided with heating means. This means might conveniently include piping (not shown) for circulating steam through suitable cored passages in the shaft 78 and through the interior of the bed roller 79. Each of the brackets 75 and 76 has formed therein, above the bearings 77 a vertically extending way 80 in which a bearing block 81 is vertically slidable. The bearing blocks 81 are adapted to support a shaft 82 carrying a weighted pressure roller 83.

It will be readily understood that when the felt strip 45 is passed around and between the rollers 79 and 83 in the manner shown in Fig. 1 the weighted pressure roller 83, which is freely slidable vertically relative to the bed roller 79, will compress the surface of the strip 45 against the bed roller 79.

It is, of course, understood that the above described means for applying surface pressure is illustrative only, the exact details of construction being immaterial, it being well within the scope of the invention to use equivalent means of applying the desired pressure to the strip 45. If desired, a spring or screw actuated roller may be used in place of the roller 83. In the preferred form of my invention, however, I prefer to use the weighted roller 83. I have found that a roller of this character has a unique action, and that when used in connection with the step of submerging a strip of felt in a hot asphalt greatly facilitates the dehydration and impregnation of the felt, accomplishing entirely new results never accomplished before in the manufacture of roofing material.

In this connection I will refer to the dehydrating and saturating action which is carried on in the tanks 13 and 14. It will be seen that the strip of felt 45 is submerged in the bodies of asphalt 33 and 34 but a very shallow distance, and when the strip of felt is moving at a normal rate of speed, it will be submerged for a very short length of time. In practice, the strip

of felt is moved at such a rate of speed that the two surfaces thereof will be thoroughly coated, but at the same time each successive portion, as it is treated, is removed from the body of hot asphalt before the vapors therein are formed to any great extent, in order that practically all of the liberation of the vapors will occur after the treated portion of the strip of felt has been withdrawn from the body of hot asphalt. This action may be particularly described with respect to the tank 13. The strip of felt passes downwardly into the body of hot asphalt 33, as indicated by the arrow K. The strip of felt passes around and below the guide means or roll 40 and then passes directly upward in the direction of 10 the pressure mechanism P, and each successive portion will be therefore submerged and will be quickly emerged from the body of hot asphalt 33 so that the liberation of the vapors will not occur to any material extent until the treated portion is above the surface level of the body of hot asphalt 33, where such liberation will not cause a foaming of the asphalt contained in the tank.

Shortly after issuing from the body of asphalt 33 the felt strip 45 is passed between the rollers 83 and 79 of the pressure mechanism P, the squeezing action imparted thereby not only serving to press or wring the strip in such a manner as to remove the excess asphalt carried on the surfaces thereof so as to facilitate the subsequent escape of moisture vapors from the strip but also to compress the asphalt forcibly into the body of the strip, thoroughly distributing the asphalt throughout the strip. This squeezing action also removes any foam or bubbles carried by the strip 45 and prevents this foam from being entrained into the body of asphalt in the succeeding submerging tank.

I have found that the action of these pressure rollers very materially quickens the thorough impregnation of the felt strip. In carrying on the process of impregnating roofing material without the use of the pressure rollers, I have found that while submerging the strip in asphalt thoroughly coats the outer surfaces thereof, there are frequently many patches in the strip in which the asphalt does not readily penetrate into the pores of the felt so that an even distribution and a uniform depth of penetration is accomplished only after repeated submerging steps.

By the use of the pressure rollers of my invention, I am enabled to obtain substantially complete distribution and a uniform depth of penetration with only a single submerging step. This I believe is due to the fact that as the strip 45 is passed between the rollers 83 and 79 the excess asphalt on the surface of the strip which is prevented by the squeezing action of the rollers from passing therebetween, builds up, as indicated at 60 D forming an eddy or back-wash which serves to constantly distribute the asphalt evenly over the entire surface of the strip as the strip is subjected to the surface compression by the rollers. This compression forces the asphalt into the pores 65 of the strip to a substantially uniform depth and causes the strip to emerge from between the rollers, free from excess asphalt on the exterior surfaces thereof, which allows perfect freedom for the escape of moisture vapor.

The hot asphalt in the tank 11 is at a temperature of 400° to 450° F. and therefore the moisture in the felt strip is very quickly vaporized. The dehydrating action which results from this vaporization of the moisture and the liberation of 75

such moisture vapors outside the body of saturant, being assisted by the above described action of the pressure rollers, is very quickly and efficiently performed. This type of treatment is performed in each of the compartments 13 and 14, although I have found that only the one surface compression step is ordinarily necessary for a substantially complete dehydration of the felt strip. When the strip of felt has passed around the roll 48, it has usually been thoroughly dehydrated and is ready for subsequent treatments in the compartments 20 and 22.

It is, of course, obvious that upon submerging the strip of felt in the body of hot asphalt there is an immediate tendency toward vaporization of the moisture content of the felt, and a small amount of vapors may be given off immediately even though the strip of felt is very quickly removed from the body of hot asphalt. There is a possibility, therefore, that a slight amount of foam may collect on the surface of each body of hot asphalt 33 and 34. This formation of foam, however, is so negligible that the foam does not collect to the extent that the steps of the method will be impaired. By reason of the fact that the hot asphalt is continually overflowing the partition 12 and the end wall 35 of the tanks 13 and 14, there is a continuous surface flow of the asphalt in the direction of the left end of the tank structure 11. Therefore, any foam which is formed on the surface of either of the bodies of hot asphalt 33 or 34 is immediately moved in a leftward direction toward the partition 12 or the end wall 35. In passing over this partition and end wall the spilling action tends to break up any foam that might have collected on the surface of the asphalt so that substantially no foam is carried from one tank into the other. It is to be noted that this continuous flow of hot asphalt tends to continually and immediately remove all foam from a position on the surface of the hot asphalt where the strip of felt will be contacted. This is particularly true with respect to the place where the strip of felt enters the hot asphalt. It is particularly desirable because there will be no foam adhering to the raw felt as it passes into the body of hot asphalt, and therefore there will be no collection of bubbles or foam on the surface of the felt which might impair penetration of the hot asphalt into the pores of the felt.

The operation of the pressure mechanisms P' and P'' adjacent the compartments 20 and 22 of the tank 15 is the same as that of the pressure mechanism P described above, the eddy of excess asphalt being built up at the points E and F, and the pressure rollers 83 and 79 serving to force the asphalt into the pores of the felt in an evenly distributed manner and to a substantially uniform depth.

As before stated, the pressure mechanisms P, P', and P'' need not all be used at the same time or at the identical intervals in the process which I have disclosed. I have found that in some instances the mechanism P may be dispensed with, and that satisfactory dehydration is accomplished by the guide rollers 40 and 41, the action thereof in rapidly submerging and withdrawing the felt strip being all that is necessary to accomplish substantially complete dehydration. This is substantially true in treating a light weight felt or one that has a comparatively low moisture content. In this event the pressure mechanism P' may be used to facilitate the quick impregnation of the strip by forcing the asphalt into the

pores of the felt in an evenly distributed manner and to a uniform depth.

I have also found by experiment that it is sometimes unnecessary to carry on the submerging steps and the surface pressure step in the compartment 22; in this case, the strip 45 is passed without additional submersions to the guide rolls 65 or to suitable cooling loopers directly from the roll 59, as indicated by the dotted lines 45a in Fig. 1. If the tank 22 is not used, the gauging rollers H serve as the final gauging mechanism in the process, acting to remove the excess asphalt from the strip so that the strip will be in suitable condition for drying when delivered to the cooling loopers above referred to. However, in the preferred form of my invention I consider it desirable to provide the compartment 22 and to carry on the submerging steps and the surface compression step therein in order that any desired degree of saturation of the strip may be accomplished.

When, as preferred, the compartment 22 is utilized, the gauging rollers G are used as the final gauging mechanism serving to compress the strip 45 to the desired thickness and removing the surface asphalt therefrom.

It is believed that from the foregoing the method of my invention, as well as the apparatus which I have produced, may be readily understood. The various steps of the process and the operation of the apparatus of my invention may be epitomized as follows:

The strip of rag-felt or paper which is commonly used is of a soft and porous nature and has not been previously treated to remove the moisture. Therefore, the moisture content thereof may be as high as six or seven per cent. While mentioning the strip of felt which I have indicated by the numeral 45, I wish it to be strictly understood that my invention is not limited to the treatment of any particular absorbent material. The strip of felt 45 passes, as indicated by the arrow K, from the initial rolls 46 into the tank 13 and around and below the roll 40, being submerged in the hot asphalt 33. The strip then passes upwardly through the pressure mechanism. It should be understood, however, that I do not consider the pressure mechanism P essential at this point, having merely included it in the initial saturating steps to illustrate the feasibility of its use at this point. I have obtained far superior dehydrating efficiencies than those obtained in other processes by merely quickly submerging the strip and quickly withdrawing it before the liberation of the moisture vapors occurs and allowing these vapors to escape before again submerging the strip. The primary feature of the pressure mechanism is the function of forcing the asphalt into the body of the felt strip so that even distribution and uniform depth of penetration can be accomplished throughout the entire strip. The strip then passes downwardly around the roll 41 in the tank 14 and is thus caused to be submerged in the body of hot asphalt 34. After emerging from the tank 14 the strip is passed around the elevated roll 48 at which time it is ordinarily thoroughly dehydrated. The strip is then successively passed through the following steps, submerging in the tank 20, applying surface pressure thereto by the mechanism P', again submerging in the tank 20, passing through the gauging mechanism to remove the excess asphalt therefrom, repeating the submerging steps and the surface pressure step in the tank 22, and 75

finally passing through the gauging rollers G to finally remove the surplus asphalt therefrom.

As a specific example of the factors involved in my process, the following facts obtained from 5 actual use of my invention are recited.

Referring to Fig. 1, I have used my invention in actual practice where the roll 40 or 41 is 9 inches in diameter and is submerged to a depth of 1 to 1½ inches below the surface of the body of saturant in which it is submerged, and under 10 these conditions the amount of felt in connection with this particular submerging step is approximately 26 lineal inches. The amount of felt which is on the exterior of the bodies of hot saturant between any two succeeding submerging steps, such as between the roll 40 and the roll 41, is approximately 18 feet.

In the example now referred to the felt is traveling at 195 feet per minute. This is figured on 20 325 rolls of felt per hour, the rolls being 36 feet to the roll of 85 pound slate surfaced roofing. The felt used is 50-D felt. On this basis the rate of travel of the felt is 2,340 inches per minute. With 25 26 lineal inches of the felt being submerged, any given portion of the strip or roll of felt will remain submerged for approximately two-thirds of a second. In other words, it requires approximately two-thirds of a second for the felt to travel from the point where it enters the hot saturant to the 30 point where it emerges from the hot saturant.

The time limits involved in my process must be varied in accordance with the character and weight of the felt being treated, the moisture content of the felt, and the quality, character, or consistency of the saturant used. At times it will be desirable to submerge the felt for a period of two seconds, and at other times it will be desirable to submerge the felt for a period of less than two-thirds of a second. Likewise, the speed of the 35 apparatus may be increased or decreased and the depth of submergence may be increased or decreased as found desirable by those skilled in the art in the practice of my invention.

The essence of the invention and the basis for 40 the process are that the felt is submerged in the hot asphalt for the purpose of coating or applying the hot asphalt to both sides thereof and is quickly removed so that the vapors produced by the vaporization of the moisture or gases produced 45 as a result of the heat will be released or liberated from the felt outside the body of saturant to avoid, as far as possible, the formation of foam. As pointed out heretofore, the formation of foam has two injurious actions. First, it destroys the quality 50 of the hot asphalt by providing a large body of foam and impurities on the surface thereof, and, second, the foam adheres to the surface of the felt and prevents proper saturating of the felt.

55 In the foregoing I have given factors which are involved in performing the process of my invention under certain operating conditions, and from these figures those skilled in the art can, by making minor adjustments, suit the process to 60 saturate different felts in accordance with my invention.

In setting up the apparatus for performing the process of my invention the parts may be ar-

ranged as disclosed in the drawing and in accordance with the dimensions given heretofore. The sizes of the parts and the speed of operation may also be in accordance with the foregoing specific example. If, during the performance of 5 the process foaming occurs which produces the bad effects pointed out heretofore, the time of submergence of the felt may be shortened. This will be quite obvious to one skilled in the art because, as specifically pointed out heretofore, 10 the length and time of submergence control the amount of foam which occurs. By shortening the time of submergence the amount of foaming will be reduced. Likewise, the period of time which the felt is retained on the exterior of the 15 hot asphalt may be varied in order that the time will be proper to allow the liberation of vapors from the felt. If, on the other hand, the felt is not properly saturated and there is an absence of any material or substantial foaming, 20 the operator skilled in the art will know that the time of submergence is not sufficiently long to coat or impregnate the surfaces of the felt to obtain the results pointed out in this specification. The operator will thereupon change the time of 25 submergence either by lowering the roller or by slowing up the speed of the apparatus.

In view of the fact as pointed out heretofore, it is impossible to give definite time limits. I have therefore pointed out the important features 30 of my invention and the steps which must be performed in order to accomplish the results of my invention. With the information given a skilled mechanic may readily adjust the various factors in order to obtain these results. 35

I believe my invention to be broadly new, and I have therefore written the claims in accordance with the scope of my invention, and it is desired that these claims be construed in accordance with the broad defines of my invention as fully described therein. 40

I claim as my invention:

1. A process of the class described, including the steps of: providing a body of hot saturant; completely submerging a sheet of absorbent in 45 said body of hot saturant only for such a length of time that the surfaces of said sheet of absorbent will be coated but not sufficiently long that material vaporization of moisture will occur in said sheet of absorbent; removing said sheet 50 of absorbent from said body of hot saturant; and retaining said sheet of absorbent on the exterior of said body of hot saturant until the vapors formed in said sheet of adsorbent have been liberated. 55

2. A process of the class described, including the steps of: providing a body of hot saturant; completely submerging a sheet of absorbent in said body of hot saturant; removing said sheet of absorbent from said body of hot saturant when 60 the surfaces of said sheet of absorbent have been coated by said hot saturant but before any material vaporization of moisture occurs in said sheet of absorbent; and retaining said sheet of absorbent on the exterior of said body of hot 65 saturant until the vapors formed in said sheet of absorbent have been liberated.

HAROLD D. BROWN.
